UNITED STATES PATENT OFFICE.

IRVING LEWIN, OF NEW YORK, N. Y., ASSIGNOR TO UNITED RIBBON COMPANY, OF NEW YORK, N. Y., A FIRM.

NECKTIE.

1,004,444.

Specification of Letters Patent. Patented Sept. 26, 1911.

Application filed April 19, 1911. Serial No. 622,138.

To all whom it may concern:

Be it known that I, IRVING LEWIN, a citizen of the United States, and a resident of the city of New York, borough of Manhattan, in the county and State of New York, have invented a new and Improved Necktie, of which the following is a full, clear, and exact description.

My invention relates to a new and improved form of reversible entirely woven necktie.

An object of my invention is to provide an all-woven necktie which comes from the loom completely woven, having the neckband thereof of the common tubular construction and the ends forming with the neckband, a reversible open-ended four-in-hand tie.

A further object of my invention is to provide an entirely machine-made and automatically shaped tie, the ends of which consist of three plies, one woven beneath the other, and one of said plies being between the outer two.

A further object of my invention is to provide a tie of the above indicated construction, the weaving thread of which is integral end to end, to eliminate the raw edges commonly found on ties of similar constructions.

With the above and other objects in view, as will more fully hereinafter appear, the present invention consists in certain novel details of construction and arrangement of parts hereinafter fully described, illustrated in the accompanying drawings, and more particularly pointed out in the appended claim.

Reference is to be had to the accompanying drawings, forming a part of this specification, in which similar characters of reference indicate corresponding parts in all the figures, and in which—

Figure 1 is a plan view of my invention showing a preferred embodiment thereof; Fig. 2 is a plan view of one end of the same, parts broken away, with the folded ends open; Fig. 3 is a transverse sectional view taken on the line 3—3 of Fig. 1; and Fig. 4

is a transverse sectional view taken on the line 4—4 of Fig. 1.

Described more in detail, my improved tie is entirely machine made coming from the loom complete as shown, and comprises a central tubular neck portion 5, both ends of which are flared outward to form a wing connection 6 between the ends 7 and the tubular or neck portion 5 to form a tying portion. The end portions come from the loom in folded condition, as shown in Fig. 1, which folded condition is formed by folded plies comprising a lower ply 8, an intermediate ply 9, and, as shown in Fig. 3, an upper and middle ply 10. Along the end 11, each edge is automatically stitched by the loom at several spaced-apart points 12, in order to retain the end in a flat condition.

My improved tie is of one continuous piece of material shaped as shown, the weaving thread of which is one continuous thread, thereby preventing the showing of any raw edges. As shown, the plies 8 and 10 merge into each other at 13, to form the tubular neck portion 5.

Many changes could be made in the above construction and many apparently widely different embodiments of this invention could be made without departing from the scope thereof. It is intended that all matters contained herein in the above description or shown in the accompanying drawings, shall be interpreted as illustrative and not in a limiting sense. It is also to be understood that the language used in the following claim is merely intended to cover all the generic and specific features of the invention herein described, and all statements of the scope of the invention, which, as a matter of language, might be said to fall therebetween, and that materials, sizes and relativities of parts are non-essential, except as called for in the claim.

Having thus described my invention, I claim as new and desire to secure by Letters Patent:

A reversible necktie, consisting of one flat continuous piece of woven material, having

a tubular seamless neck portion and open end portions integral with said tubular portion, each end portion comprising three superimposed plies, the lower ply and the 5 intermediate ply being both integral at one edge with the opposite edges of the upper or middle ply.

In testimony whereof I have signed my name to this specification in the presence of two subscribing witnesses.

IRVING LEWIN.
